UNITED STATES PATENT OFFICE

2,541,784

ROOF CONSTRUCTION

Harold S. Shannon, Detroit, Mich., assignor to
 National Steel Corporation, a corporation of
 Delaware

Application June 22, 1946, Serial No. 678,636

5 Claims. (Cl. 108—1)

1

This invention relates generally to building construction and more particularly to roof framing structure therefor.

As is well known, it is the practice in the building industry to construct roof framing, such as end gable frames and intermediate trusses, in place on the job. To reduce the cost of building construction, it has been proposed to factory fabricate end frames and trusses by mass production methods and supply them ready to be hoisted into place in the roof assembly. While this no doubt decreases cost of fabrication of end frames and trusses, other problems and disadvantages arise which are equally undesirable. For example, trusses are usually so large that they are difficult to store, handle, package and ship. Also roof ridge members are usually of such length that they, like the end frames and trusses, are unwieldy to handle, package and ship. In addition, factory fabricated trusses and roof framing structures present problems with respect to the connection of the trusses and frames together by the ridge member and so, in general, factory fabricated roof structures have not been entirely satisfactory.

Accordingly, it is an object of the present invention to provide new and improved factory fabricated roofing sub-assemblies of a character to overcome the above mentioned objections.

Another object of the invention is to provide new and improved roof structure sub-assemblies of a character and arrangement such that they may be readily assembled into the roof framework assembly.

Another object of the invention is to provide a roof structure of interchangeable, prefabricated sub-assemblies to facilitate roof erection and decrease cost thereof.

A further object of the invention is to provide prefabricated roof sub-assemblies of a character which may be conveniently handled, packaged and shipped.

Other objects of the invention will become apparent from the following detailed description taken in connection with the accompanying drawings in which:

Figure 1 is an isometric view of a building roof structure embodying features of the present invention;

Figure 2 is a fragmentary, isometric view of the roof structure with parts thereof shown displaced to show certain details of construction;

Figure 3 is a fragmentary, isometric view of a detail of the roof framework structure;

Figure 4 is a fragmentary, elevational view

partly broken away and in section showing interconnections between a truss and ridge structure of the roof framing;

Figure 5 is a horizontal sectional view of the roof framework structure taken along the line 5—5 of Figure 1;

Figure 6 is an isometric view of an intermediate truss-sub-assembly of the roof framework structure; and,

10 Figure 7 is a view similar to Figure 6 of an end frame section of the roof framework structure.

In the drawings which illustrate a preferred embodiment of the invention, the building includes corner columns 10, pairs of intermediate, 15 oppositely disposed, side wall columns 11 and intermediate end wall columns 12. Supported on the side wall columns 10, 11 are girders 13 seating on and secured to cap plates 14 on the upper ends of the columns. Preferably the girders 13 are of

20 sectional construction each section, as at 15, spanning a pair of the adjacent columns around the walls of the building. The roof structure includes, end gable frames or trusses 16, spaced, intermediate frames or trusses 17 and a ridge member 18.

25 The end gable frames 16 and intermediate trusses 17 are supported by the columns 10, 11 and are connected together by the ridge member 18. As shown in Figure 1, the end gable frames 16 seat on the cap plates 14 of the corner columns 10 and 30 on the cap plates of the intermediate end wall column 12 whereas the intermediate trusses seat on and span the side wall girders at each of the pair of oppositely disposed intermediate columns 11.

35 In order to reduce building costs and to facilitate packaging, handling and shipping of the building roof structure, the gable roof end frames 16 each comprises a pair of prefabricated sub-assemblies, or sections 20 for connection together at the building erection site. The pre-assembled sections 20 of each gable end frame 16 are joined together at or below the ridge member 18 and are made alike and interchangeable to facilitate assembly. Referring in detail to the gable end

40 frames 16 and particularly to Figure 7 which shows one of the pre-assembled sections 20 thereof, this frame section comprises a lower horizontal frame member 22, an upper angularly disposed frame member 23 and a vertically extending frame member 24. These frame members 22, 23 and 24 are secured together at their ends, 45 preferably by welding, in the form of a right angle triangle comprising one-half of the isosceles triangular shape of a gable end frame.

50 Preferably, the end gable frame members 22, 23

55

and 24 are of channel-form for strength and rigidity, the lower horizontal frame member sections 22 being also the end wall girders of the building. These frame members or end wall girders 22, like the side wall girders 13, each has a web 25, a lower seating flange 26 and an upper supporting flange 27, the flanges 26, 27 preferably being directed inwardly of the building. The upper, angularly disposed frame member 23 is arranged so that its flanges are directed downwardly, the upper end of the vertical frame member 24 being received between and welded to the downwardly directed flanges of member 23. The lower end of the vertical frame member 24 seats on and is preferably welded at its lower end to a spacer plate 29 which in turn seats on and is preferably welded flat to the upper supporting flange 27 of the horizontal frame member 22. The vertical frame member 24 comprises a web 30, an inner side flange 31 and an outer side flange 32 extending vertically between the upper surface of the spacer plate 29 and the upper end of the angularly disposed channel frame member 23. At the outer ends of each of the frame sections 20, an angle bracket 34 has a vertical leg 35 welded to the inner side flange of the angle frame member 23 and to the lower horizontal frame member 22, reinforcing the structure, the other or horizontal leg 36 of the bracket 34 seating on the side wall girder 13. This horizontal bracket leg 36 may be provided with an aperture 37 aligning with an aperture in the upper supporting flange of the girder 13 and receiving a self-threading screw 38 for securing the parts together.

The pre-assembled, gable end frame sections 20 are connected together into a rigid gable end frame by a pair of splice plates 40. As shown, the pre-assembled pair of frame sections 20 are brought together with the channel webs 30 of the vertical frame members 24 in back-to-back relation. To each of the pair of corresponding, oppositely directed flanges 31, 32 of the pair of frame members 24, is secured one of the splice plates 40. These splice plates 40 are elongated and seat flat against the flanges 31, 32, overlapping the joint therebetween and preferably extending upwardly to overlap the joint between the inner opposed ends of the angularly disposed chord members 23. The flanges 31, 32, of the splice plates 40, are preferably secured together by self-threading screws 41 threaded into apertures 42 provided in the flanges 31, 32 of the vertical frame members 24.

The intermediate frames or trusses 17, like the end frames 16, each comprises a pair of prefabricated half frames or sections 44 so as to facilitate packaging and handling of the structure and also to facilitate erection of the roof framing. As shown in Figure 6, the prefabricated frame section 44 of the trusses 17 is similar to the prefabricated frame section 20 of the gable end frames 16. Each of the truss frame sections 44 comprises a lower, horizontal chord member section 45, an upper angularly disposed chord member 23 and a vertical support or web 24, the chord members 23 and 24 being preferably of the same channel stock and of the same lengths as the corresponding end frame members, designated by the same numerals. Like the end frame members, the truss frame members 23, 24 and 44 are secured together, preferably by welding, at the ends thereof, forming triangular frames. The upper truss chord member 23, like the corresponding end frame member 23, is arranged so that its

flanges are directed downwardly. The lower chord section member 45 may be of the same stock as the upper frame member 23 and this lower chord section 45 is arranged with its side flanges extending upwardly. Vertically and angularly disposed webs or struts 48, 49 connect and reinforce the upper and lower truss chords 23, 45, the webs having their opposite ends received in and preferably welded to the channel frame members. The half sections of each truss 17 are secured together by pairs of the splice plates 40 secured to the upright flanges 31, 32 by the self-threading screws 41. At their outer ends, the truss sections 44 are provided with pairs of the brackets 34 for securing the ends of the trusses 17 to the side wall girders 13.

In order to facilitate packaging and handling of the ridge member 18 and to facilitate generally the assembly of the roof framing, the ridge member 18 comprises a number of sections 50. Each of these ridge member sections 50 is of a length to span a pair of the trusses 17 or to span an end frame 16 and an adjacent truss 17. Each of the ridge member sections 50 comprises a pair of parallel plate-like members 51 spaced apart by U-shaped spacer members 52 welded thereto at intervals along the length thereof. The parallel ridge members 51 preferably have inturned, upper, reinforcing flanges 53 and lower, out-turned, reinforcing flanges 54. At opposite ends of each ridge member section 50, the U-shaped spacer members 52 constitute attaching means in the form of hook receivers, such as loops or eyes, to engage over co-operable attaching means 55 or an upstanding hook 56 carried by each of the splice plates 40. These hooks 56 may be welded to the splice plates 40 adjacent the upper ends thereof. Intermediate its ends, each of the hooks 56 has an upper offset portion providing an upwardly facing seat 58 for the loop ends 52 of the ridge member sections 50 to rest thereon. Thus, the ridge member sections 50 locate the end gable frames 16 and the intermediate trusses 17 relative to each other and connect them together, it being only necessary to set the ridge member sections in place over the hooks 56, carried by the splice plates 40. Each of the ridge member sections 50 carries a pair of angularly disposed connecting members or braces 60 which, in addition to bracing the framing, connect the ridge member sections 50 to the end frames 22 and to the intermediate trusses 17. These braces 60 are preferably of channel form for strength and rigidity, each having a web 61 and depending, side reinforcing flanges 62, 63. The upper ends of the braces 60 position between the spaced ridge members 51 and are preferably pivotally connected thereto by a pivot pin 65 extending through apertures in the depending flanges 62, 63 of the braces 60. These upper ends of each pair of braces 60 are spaced apart intermediate the ends of the respective ridge member sections 50, extending downwardly therefrom respectively toward the adjacent splice plates 40 to which they are attached. At their lower ends, the brace flanges 62, 63 are outturned, as at 66, to seat flat against the adjacent splice plate 40 to which they may be secured by self-threading screws 67 or by other suitable means.

From the foregoing description, it will be seen that the end gable frames 16, trusses 17 and ridge member 18 may be packaged and shipped to a building erection site in sections where the sections may be readily assembled into the roof framing of the building. The end gable frames

16 may be assembled on the ground and then hoisted into position in the structure. To assemble these end gable frames, two of the half sections 20 are brought together with the upright channel members 24 thereof in back-to-back relation and the splice plates 40 are then applied and secured to the members 24 by the self-threading screws 41. The end frames 16 may then be hoisted into place and the chord or girder members 22 thereof bolted to the column cap plates 14. The self-threading screws 38 may then be applied and tightened down to secure the outer ends of the end frames to the opposite side wall girders 15. The intermediate frames or trusses 17 are assembled similarly to the end frames and hoisted into place. As each truss is set in place on the girders 15, a connecting section 50 of the ridge member may be set in place locating the truss and connecting it to the adjacent end frame or to another truss as the case may be. This is done simply by lowering the ridge member section with its looped ends 52 over the upstanding hooks 56 carried by the splice plates 40. Later, or when desired, the pivoted connectors or braces 60 may be swung up and their lower ends secured by self-threading screws to the splice plates 40, thus securing the ridge member sections, trusses and end frames together into a rigid roof framework.

I claim:

1. A building truss comprising, a pair of connected together truss sections, each of the truss sections having a horizontal channel chord member, an angularly disposed channel chord member and an upright connecting member connecting the channel chord members together adjacent their inner ends, the chord members of each truss section and the upright connecting member being arranged as a right angle triangle with the angularly disposed chord member defining the hypotenuse and being coplanar with the sides of the channel chord members directed toward each other, means for supporting the truss sections adjacent their outer ends on a building framework and also connecting the ends of the chord members of each section together, reinforcing web members having opposite end portions thereof received in and secured to the channel chord members of each section, and splice plates overlying and connecting the upright connecting members of the sections together in back-to-back relationship.

2. In a building roof construction, the combination comprising, a plurality of spaced parallel trusses, each truss comprising a pair of pre-assembled truss sections and each truss section having a horizontal chord member, an inclined chord member, a vertical connecting member connecting together the spaced inner ends of the chord members and means connecting together the outer ends of the chord members, each pair of truss sections being arranged with the vertical members in back-to-back relationship, and each truss comprising splice members overlying and connected to the sides of the vertical members of the pair of truss sections and connecting the truss sections together with the inclined chord members adjoining at the ridge of the roof and serving as roof rafters, ridge member sections respectively extending between adjacent trusses and having attachment means, attachment means carried by the splice plate members cooperable with said attachment means on the ridge member sections attaching the ridge member sections and the trusses together for

restraining lateral movement of the ridge member sections relative to the trusses, and bracing means carried by the ridge member sections connected to the trusses acting to hold the ridge member sections against upward movement relative to the trusses.

3. In a building roof construction, the combination comprising, a truss including a pair of pre-assembled truss sections, each truss section having a horizontal chord member, an inclined chord member, a vertical connecting member connecting together the spaced inner ends of the chord members and means connecting together the outer ends of the chord members, the pair of truss sections being arranged with the vertical members in back-to-back relationship, and the truss including splice members overlying and connected to the sides of the vertical members of the pair of truss sections and connecting the truss sections together with the inclined chord members adjoining at the ridge of the roof and serving as roof rafters, attachment means carried by the truss restraining lateral movement of the ridge member, means carried by the ridge member cooperable with the attachment means, and a bracing member carried by the ridge member connecting the ridge member to the truss.

4. In a building roof construction, the combination comprising, a truss including a pair of pre-assembled truss sections, each truss section having a horizontal chord member, an inclined chord member, a vertical connecting member connecting together the spaced inner ends of the chord members and means connecting together the outer ends of the end members, the pair of truss sections being arranged with the vertical members in back-to-back relationship, and the truss including a splice plate member overlying and connected to the sides of the vertical members of the pair of truss sections and connecting the truss sections together with the inclined chord members adjoining at the ridge of the roof and serving as roof rafters, a ridge member attached to the splice plate member, and a brace carried by the ridge member having one end attached thereto and having its other end attached to the splice plate member to provide with the abutting portion of said chords a ridge structure for the roof construction.

5. In a building roof construction, the combination comprising, a plurality of spaced parallel trusses, each truss comprising a pair of pre-assembled truss sections and each truss section having a horizontal chord member, an inclined chord member, a vertical connecting member connecting together the spaced inner ends of the chord members and means connecting together the outer ends of the chord members, each pair of truss sections being arranged with the vertical members in back-to-back relationship, and each truss comprising splice members overlying and connected to the sides of the vertical members of the pair of truss sections and connecting the truss sections together with the inclined chord members adjoining at the ridge of the roof and serving as roof rafters, a plurality of ridge member sections respectively extending between adjacent trusses, attachment means carried by the trusses, and attachment means carried by the ridge member sections cooperable with the truss attachment means attaching the ridge member sections and the trusses together so that said ridge members and said adjoined

chords provide the ridge structure of said roof construction.
